UNITED STATES PATENT OFFICE.

ROBERT E. ADKINS, OF CHICAGO, ILLINOIS.

SPRING-LOCK.

SPECIFICATION forming part of Letters Patent No. 600,701, dated March 15, 1898.

Application filed June 1, 1897. Serial No. 639,024. (No model.)

To all whom it may concern:

Be it known that I, ROBERT E. ADKINS, a citizen of the United States, residing at Chicago, in the county of Cook and State of Illinois, have invented certain new and useful Improvements in Spring-Locks, of which the following is a specification.

The invention consists in the features of novelty that are hereinafter fully described 10 with reference to the accompanying drawings, which are made a part of this specification, and in which—

Figure 1 is an elevation of a lock embodying my invention, the back plate of the lock-case being omitted and one of the parts which is carried thereby being indicated by dotted lines. Fig. 2 is a sectional elevation thereof, the section being taken in irregular planes. Fig. 3 is a detail view of some of the parts 15 shown in Fig. 2, showing their positions as the door is just being opened or closed. Fig. 4 is a perspective view of the bolt. Fig. 5 is a perspective view of the detent for holding the bolt retracted and its actuating mechanism. Fig. 6 is a section on the line 6 6, Fig. 1, showing in detail the means for supporting the rocker of the detent. Fig. 7 is a face view of the keeper. Fig. 8 is a face view of a keeper 20 modified construction.

30 A represents the lock-case; B, the keeper; C, the bolt, and D the spring by which the bolt is projected when not restrained by the means hereinafter described for holding it retracted. The projecting portion c of the bolt 35 is without any bevel on its outer face. Its rear end c' works in a guide a, which is preferably cast with the case. Near its rear end it is provided with a pair of lugs c'', which project toward the front a' of the case and 40 are engaged, respectively, by a pair of arms E, which are carried by and project in opposite directions from the spindle F of the knob G. This is a well-known means for causing the bolt to be retracted by rotation of the 45 knob G in either direction.

The lock has means for automatically locking the bolt in projected position, and a feature of the invention consists in providing means under the control of the knob by which 50 the bolt is retracted for unlocking it. To this end the bolt is provided with a socket into which projects the extremity f of the spindle

F, and the spindle is made capable of end-wise movement for the purpose of moving its extremity f into or out of engagement with the bolt. Its engagement with the bolt is effected automatically by a coiled spring H, which surrounds a reduced portion of the spindle, bears at one end against the shoulder resulting from this reduction, and bears at 60 the other end against an internal shoulder of the hollow boss I, through which the spindle passes. Its disengagement may be effected by an outward pull upon the knob.

In order to permit the bolt to be retracted 65 by the use of a key, it is provided on its inner face, near its rear end, with a lug c², which is located in the path of an arm J, pivoted to the rear plate a² and connected by a flat post J' or any other suitable means with the barrel or cylinder in which the tumblers are disposed. This barrel or cylinder is not shown in the drawings for the reason that it forms no part of the present invention and its construction is well understood by those skilled 70 in the art. Before the bolt can be retracted by this arm J it is of course necessary to disengage the spindle F from it, and to this end I dispose within the opening of the bolt a short pin K, which is secured to one end of a 75 plate-spring K', the other end of which is secured to the bolt. The formation of this spring is such that normally it holds the pin K in the position shown in Fig. 2—i. e., projecting some distance from the face of the 80 bolt and only partly into the opening. This spring is so disposed that as the arm J moves from the position indicated by dotted lines in Fig. 1 in moving toward the lug c² it engages the spring K' and forces it toward the bolt, 85 and in doing so it forces the pin K farther into the opening of the bolt, causing it to engage the end of the spindle and force the latter out of the opening, the pin K being of course sufficiently long to accomplish this result. 90

In order to lock the bolt in retracted position, it is provided with a notch so disposed that when retracted it may receive a pin L, carried by a lever L', which is secured to the 100 spindle m of a small knob M. This lever L' is prevented from moving at random by a spring N, which bears against the side of the spindle m, said spindle being provided with

two flat surfaces, as indicated by dotted lines in Fig. 1, so disposed that when it is in one position the spring will bear against one of them and when it is in the other position the 5 spring will bear against the other of them, thereby holding the pin L either in or out of engagement with the bolt, as the case may be. O is the part which is herein called the "rocker" and which carries the detent for 10 holding the bolt retracted when the door is open. It is disposed in an opening in the face-plate a^3 of the lock-case and is supported by a removable pin P, which is inserted in a socket in the face-plate a^3 through the opening 15 through which the bolt projects, the arrangement being such that when the bolt is in place in the lock it will engage the pin P and hold it in place. On the other hand, when the bolt is removed the pin may also be removed for the purpose of reversing the position of the rocker, for a purpose that will appear hereinafter. This rocker is capable of 20 a limited oscillatory movement about its center and is so shaped that when at one extremity of such movement a portion o upon one side of its center will project from the face-plate and when at the other extremity of such movement a portion o' upon the other side of its center will project from the face- 25 plate, their action being reciprocal. The portions o o' are hereinafter called "tappets." The rocker is held in whichever of these two positions it may be by means of a spring Q, so disposed that it exerts its pressure toward 30 the center of movement, so that when the point of contact between the spring and rocker passes a line drawn from the axis of the rocker to the fixed point from which the spring exerts its force the spring will tend to 35 accelerate its movement in the direction in which it is for the time being moving and prevent its return movement. This rocker is so disposed with relation to the keeper B that as the door opens the tappet o, which is 40 for the time being projecting from the face-plate, will come in contact with the keeper and will be forced inward, thereby causing the other tappet o' to be projected, as shown in Fig. 3. The spring Q, acting as described, 45 will hold the rocker in this position (with its tappet o withdrawn and its tappet o' projected) until the door is again closed, whereupon after the tappet o has passed the keeper the tappet o' will come in contact with the 50 keeper and will be forced inward, thereby again projecting the tappet o, as shown in Fig. 2. It is this oscillatory movement of the rocker which is utilized, first, in moving the detent R into engagement with the bolt 55 for holding it retracted while the door is open, and, secondly, in tripping the detent and permitting the bolt to be projected as the door closes. The bolt is provided with a shoulder r, in front of which the detent R is 60 moved when the rocker is moved in the act of opening the door. The shoulder r is preferably the result of a notch cut in the side of 65

the bolt. It will be understood, of course, that the door cannot be opened until the bolt is retracted, and this shoulder r is so disposed that when the bolt is in retracted position and the door is being opened the detent R may pass into engagement with the front side of the shoulder in the manner described. This, as before suggested, holds the 70 bolt in retracted position while the door is open and until in the act of closing the door the rocker is moved in the manner already described, so as to move the detent out of engagement with the bolt. 75

As the parts are shown in the drawings, they are arranged for application to a door that opens "inward." To make the lock applicable to a door which opens outward, the bolt is provided with a second shoulder r', 80 the shoulders r r' being disposed upon opposite sides of the center of motion of the rocker, and the rocker is provided with a second detent R', which when it is reversed will engage the shoulder r' and hold the bolt in retracted position in the manner already described. For an outward-opening door it is also necessary to change somewhat the construction of the keeper, and a keeper suitable for such a door is shown in Fig. 8. 85

Having thus described my invention, the following is what I claim as new therein and desire to secure by Letters Patent: 90

1. In a lock, the combination with a bolt, a spring for projecting it, and means for reTRACTING it in opposition to the force of the spring, of a rocker carrying a detent adapted to engage the bolt when in retracted position, and a pair of tappets for actuating said rocker, said tappets being so disposed that as the door 100 is being opened one of them will engage a fixed part and actuate the rocker, causing the detent to engage the bolt, and as the door is being closed the other of them will engage a fixed part and actuate the rocker, causing 105 the detent to disengage the bolt, substantially as set forth.

2. In a lock, the combination with a bolt, a spring for projecting it, and means for reTRACTING it in opposition to the force of the 110 spring, of a reversible part having a pair of tappets so disposed that as the door is being opened or closed one of them engages and is moved by a fixed part, and means actuated by said tappets for engaging and disengaging 115 the bolt, substantially as set forth.

3. In a lock, the combination with a bolt and a spring for projecting it, and means for reTRACTING it in opposition to the force of the 120 spring, said means including a knob, of means 125 for engaging the bolt and locking it in projected position, said locking means being under the control of the knob so that by manipulating the knob the bolt may be both unlocked and retracted, substantially as set 130 forth.

4. In a lock, the combination with a bolt, and a spring for projecting it, of means for reTRACTING it in opposition to the force of the

spring, said means including an endwise-movable spindle adapted to engage the bolt and lock it when projected, substantially as set forth.

- 5 5. In a lock, the combination with a bolt and a spring for projecting it, of means for retracting it in opposition to the force of the spring, said means including an endwise-movable spindle, and means under the control of the operator for locking the bolt when projected, said means including the spindle which is adapted to engage the bolt, and a spring for moving said spindle into engagement with the bolt, substantially as set forth.
- 15 6. In a lock, the combination with a bolt having an opening through it, and a spring

for projecting the bolt, of means for retracting it in opposition to the force of the spring, said means including an endwise-movable spindle adapted to project into the opening of the bolt, a spring for moving said spindle endwise in one direction, a pin projecting into the opening of the bolt and adapted to engage the end of the spindle, a spring carrying said pin, and a part adapted to be operated by connection with the key for engaging said pin and causing it to disengage the spindle from the bolt, substantially as set forth.
